BEVERAGE DISPENSING APPARATUS

Edward Freund, Long Beach, N. Y.

Application April 19, 1933, Serial No. 666,805

4 Claims. (Cl. 225—12)

My invention relates to beverage dispensing apparatus in which pipe connections extend from the beverage containers to the dispensing faucets, and air or carbonic gas pipes extend from a 5 pump or gas tank to the beverage containers for supplying the pressure for raising the beverage fluid from the containers to the dispensing faucets. And my invention relates more especially to arrangements for cleaning the beverage piping. 10 The pipe cleaning operation in such dispensing apparatus is generally performed with special portable apparatus at a time of day when the beverage dispensing apparatus is not in use, or if done during service hours, service must be temporarily discontinued because the cleaning and 15 flushing operations necessarily involve disconnecting the pipe system from the beverage containers for connection to the flushing apparatus. This method does not permit of cleaning operations being performed with proper frequency or 20 thoroughness to insure at all times the best sanitary and palatable conditions, and involves loss of the beverage fluid contained in the pipe lines extending from the containers to the dispensing 25 faucets, which if the cleaning operation were performed daily, would amount to a high percentage loss of beverage fluid plus cost of the cleaning service.

The object of my invention is to provide a 30 method and means for permitting the frequent flushing of the pipe connections, at any time or during service hours, without loss of beverage fluid contained in the pipe line, without the necessity for disconnecting the piping system from the beverage containers, and without the application of special portable apparatus.

In carrying my invention into effect I provide water connections which are connected with the 40 beverage and air or gas pressure piping, and return air pressure connections also being provided so that the beverage fluid in the pipe lines may be driven back into the containers before the cleaning operation is started, and for blowing out the water from the piping system. By this arrangement the flushing of the pipes, taps and service faucets may be carried on at any time between 45 beverage service without disconnecting the piping, or immediately preceding the tapping of each fresh container, and without disconnecting any other containers from service.

My invention is illustrated in the accompanying drawings in which, Figure 1 is a perspective view of a beverage dispensing counter with bev-

age containers, beverage piping, air or gas pressure piping, and flushing pipes permanently interconnected; Figure 2 a sectional view of one form of beverage container tap provided with a flushing connection; Figure 3 a similar view of part of another form of beverage container tap with a flushing connection; Figure 4 an elevation showing a modified arrangement of the piping system; and Figure 5 a partial sectional view of one of the air line taps showing a relief valve for reducing the air pressure in a container.

Referring to the drawings, A represents any type of beverage serving counter or bar, B the cooling box containing the usual iced coils (not shown) through which the beverage fluid flows from containers C and C' stored in refrigerator R located at any convenient place. D indicates any suitable type of air pump, E an air tank, and F (shown in dotted lines) represents a carbonic gas tank which may be employed instead of the air pump and air tank. These elements of the beverage serving bar are all of the usual and well known type and therefore require no further detailed description or illustration. Two types of beverage container taps T and T' are shown and which also are of well known construction and therefore need not be shown and described in detail, except that each tap is provided with the usual beverage nozzle 1 and an additional flushing nozzle 2 as shown in detail in Figures 2 and 3. With the type of beverage tap T, the air or gas pressure connection to the container is usually made by a tap 3 inserted into a tap-hole in the head of the container C as shown in Figure 1. With the type of tap T' the air or gas connection is usually made to a nozzle 4 projecting from the head of tap T' as shown in Figure 1. These parts are also of well known construction and need no detailed illustration or description.

The air line in Figure 1 comprises a fixed pipe 5 having any desired number of nipples projecting therefrom according to the number of beverage containers and service faucets employed and each nipple having an air cock mounted thereon; flexible pipe connections 7 from cocks 6 to air taps 3 and 4; pipe line 8 and 9 extending from manifold 5 to counter A and back to tank E, and in which pipe line is an air pressure regulating cock 10, air gauge 11, and a nipple on which air cock 12 is mounted; 100 and from pump D a pipe 13 extends to the opposite end of tank E. For pipes 9 and 13 the usual stop cocks 14 are provided at the air tank, and for the tank a relief cock 15 is provided. When a carbonic tank F is employed instead 110

of the air pump D and tank E, a pipe 16 extending from tank F is connected to pipe 9 as shown in dotted lines in Figure 1, and this connection will be provided with a valve 17. The 5 air pump and tank and the carbonic tank may be connected together as a unit as shown in Figure 1, but employed separately by shutting off air cocks 14 and opening the gas valve 17, or vice versa, as occasion may require. The beverage 10 supply lines are shown at 18 and 19 and extend from tap nozzles 1 to the usual cooling coils (not shown) in box B and which coils in turn are connected to service faucets 20 and 21. When the apparatus is in service, and employing air 15 pressure, cocks 14, 10 and 6 in the air line are open and the pump D is set to maintain the desired pressure in tank E, and regulating cock 10 is adjusted to provide the desired pressure in containers C and C' so that the beverage will 20 flow upward from the containers through pipes 18 and 19 to service faucets 20 and 21, respectively.

When the supply from a beverage container is exhausted, for instance container C, the air line 25 connection is closed at cock 6, and air tap 3 and beverage tap T are disconnected from the container. Where a beverage tap of the type shown on container C' is employed, before disconnecting tap T', its air cock 6 is closed, and in removing 30 the tap, both beverage and air line connections are simultaneously disconnected. It will be understood, of course, that water cock 24 is normally closed, it being shown open in Figure 1 only for the purpose of explaining the flushing 35 operation as herein described. In both cases tap cock 29 on taps T and T' will be closed during the disconnecting and retapping operation, and when a container is tapped, cock 29 will be reopened, and the service faucet of that line will 40 be momentarily opened and closed to start the flow into the service line. The beverage line may be flushed, as hereinafter described, either before or after tapping a fresh container.

For cleaning and flushing the beverage piping 45 a water supply line is employed as indicated at 22, and this pipe is provided with a main control cock 22' and nipples on which are mounted cocks 23 and 24, or more, according to the number of beverage lines employed. From these cocks flexible pipes 25 and 26 extend to nozzles 2 on beverage taps T and T'. Cocks 23 and 24 are normally closed so that no water flows in pipes 25 and 26. To the air cock 12 is attached a flexible tube 27 provided with a rubber socket 28 at its 50 free end, the tube being of sufficient length for attachment to either of the service faucets as shown in Figure 1. When it is desired to flush the beverage pipes, before a container is empty, it is desirable to first empty the beverage pipe 55 line so as to avoid waste of beverage fluid. To accomplish this the air cock 6 controlling the air supply to container C', for instance, is first closed to cut off air or gas supply to that container. Then tap T' is loosened in its tap hole to permit 60 air to escape from container C' in order to reduce the pressure within the container, and then tap T' is tightened again in the tap hole. Air pipe 27 is then attached to faucet 21 as shown in Figure 1 and air cock 12 is opened. The air pressure 65 from tank E being higher than the pressure in the container, the air will operate through faucet 21 to drive the beverage fluid contained in the cooling coil attached to that faucet and pipe line 19 down into the container C', whereupon tap cock 70 29 is closed. Air cock 6 is then opened again,

causing the pressure in the container to rise again to normal, but no beverage fluid will rise in pipe 19 since tap cock 29 is closed. Air cock 12 is then closed and pipe 27 disconnected from faucet 21 and water cock 24 is opened as shown 75 in Figure 1. Water will then flow for the flushing operation through pipe 26, nozzles 2 and 1 on tap T', beverage pipe 19 and connected cooling coil, and out through faucet 21 into the drain at box B. When the flushing operation has been continued the desired length of time, the service connections are restored by first closing water cock 24 and opening tap cock 29, whereupon the beverage fluid from container C' will rise in pipe 19 and drive the water remaining in that pipe and 80 attached cooling coil out through faucet 21, and as the beverage fluid begins to flow from that faucet it is closed. That beverage line will then be in normal operating condition again after having been flushed without disconnecting any of 85 the piping from the container, pressure line or service faucet, and without loss of beverage fluid. If desired, the flexible water pipe 26, may, after the flushing operation is completed, be disconnected from water cock 24 to allow the water in 90 the pipe line to drain into an empty container or other receptacle and reattaching pipe 26 to cock 24 before opening the beverage cock 29. When it is desired to flush the beverage piping after 95 a container is empty and before tapping a fresh 100 container, the air cock 6 on the air line to the empty container is closed and tap cock 29 is left open; and while the beverage tap is still attached to the container, water cock 24 is opened and the flushing water allowed to flow through the tap 105 into the empty container, thus flushing the tap, and when sufficiently flushed cock 29 is closed. The flushing water will now flow upward through nozzle 1, beverage pipe and connected cooling coil 110 and service faucet and out into the drain tray 115 at the cooling box B, as above described, and when sufficiently flushed, beverage cock 29 may be opened again to drain the water from the piping into the empty container. To flush the piping 120 for container C when a type T beverage tap 120 and separate air tap 3 are employed, the procedure is the same, except that tap 3 is loosened when it is desired to reduce the air pressure in the container.

In Figure 4, which illustrates a modified arrangement of my flushing system, the flushing control cocks are all at the service bar and only the beverage cocks 29 and a means for reducing the air pressure in the containers are located in the refrigerator. In this arrangement, A is the 125 service bar; B the cooling box containing the cooling coils connected to service faucets 20 and 21 which are mounted on the front of the box; C and C' are the beverage containers located in refrigerator R; D the air pump; E the air tank; 13 the air pipe 130 connecting the air pump and tank; 14 and 15 the shut off and relief cocks for tank E; T and T' the beverage taps having beverage nozzles 1 and flushing nozzles 2. These parts of the apparatus are all similar to those shown in Figure 140. From air tank E extends air pipe 9 which is connected to air manifold 30 to which is connected the air gauge 11 and stop-cock 12 for the flushing air pipe 27. This pipe is provided with the rubber socket 28 for attachment to beverage 145 faucets 20 and 21. From the air manifold 30 a number of nipples project on which air cocks 31 are mounted, and from these cocks extend air pipes 32 which lead into refrigerator R. To pipes 32, within the refrigerator, flexible air tubes 150

7 are coupled by any well known type of screw coupling 33. Cocks 31 are employed to regulate and shut off the air pressure to the containers.

The flushing line may include both hot and cold water, and in this illustration pipes 35 and 36 indicate the hot and cold water supply, respectively, and these pipes are connected through cocks 37 and 38, respectively, to a four-way fitting or mixer 39. From the mixer 39 a short pipe 10 or nipple extends to a T 40 to the opposite outlets of which water pipes 41 and 42 are connected. These pipes extend into the refrigerator where flexible extensions 25 and 26 connect with the flushing nozzles 2 on taps T and T'. The flow of 15 water in pipes 41 and 42 is controlled by cocks 43 and 44. To the fourth outlet of fitting 39 is screwed a valve 45 having a nozzle 46 which is provided for clearing the flushing system of water after each flushing operation by attaching the 20 air pipe 27 to this nozzle, so that when the water supply is shut off at cocks 37 and 38, the air pressure from tank E will drive the water remaining in pipes 41, 25 and 18, or pipes 42, 26 and 19, out through service faucets 20 and 21 into the drain at 25 box B.

In the air piping of Figure 4 I have shown an air vent 34 applied to air taps 3 and 4, and one form of vent which may be employed is shown in detail in Figure 5. This figure illustrates in detail 30 the air tap 3 applied to container C and is of well known construction. In this tap, air nozzle 47 to which tube 7 is attached, is provided with a collapsible rubber tube check valve 48 which prevents air or beverage fluid backing up into the air pipe. On the body part of this tap I provide an additional boss 49 which is bored out to form an air chamber 50, and a hole 51 is drilled through into the nozzle chamber. This boss is screw-threaded to receive a screw-threaded cap 52 having a hole 35 drilled through to receive and act as a guide for the vent pin 34. This hole is beveled on the inner side of the cap to form a valve seat 53. Pin 34 is angular in cross section and of a length to enter hole 51 which serves as a guide 40 for the inner end of the pin. This pin moves freely in the guide holes and the flat sides from vent spaces for the air to escape. The pin carries a beveled valve disk 54 which is held seated on valve seat 53 by the air pressure 45 in chamber 50. When it is desired to reduce the air or gas pressure in the beverage container, vent pin 34 is pressed inward allowing air to escape through holes 51 and 52, and is held until the desired reduction is obtained, and when released its valve 54 will be reseated by the internal pressure and check the further escape of air or gas from the container.

A regulated or controlled reduction of the air or gas pressure in the containers C is essential 50 to effect the return flow of beverage from pipes 18 and 19 to the containers without agitation of the beverage and stirring of sediment at the bottom of the containers. If the pressure in a container is not reduced, equal pressure from within the container and from the air supply 55 will hold the beverage stationary in the pipe line. On the other hand, if the pressure entering a faucet is considerably in excess of the pressure within a container C the beverage in the pipe line will be driven under a pressure which will stir up sediment at the bottom of the container and rile the beverage to such extent as to require considerable time to permit settlement to 60 normal condition suitable for service, if not ac-

tually rendered unfit for service. I have found that the most satisfactory way is to apply the pressure at the service faucet and then slowly reduce the pressure in the container by means of the vent at the container tap. In this way the beverage will descend slowly without stirring or agitating the contents of the container, and when the beverage line is empty, the container tap-cock is closed and the auxiliary air pipe 27 is disconnected. The air vent for the container may be closed when the beverage column begins to fall or it may be allowed to remain open until the beverage pipe is entirely empty, and when closed the pressure in the container will build up again to the normal pressure without disturbing the contents, and no air will enter the container through the tap-pipe. The air vent incidentally serves also to permit reduction of pressure within a container to normal atmospheric pressure preparatory to disconnecting a 95 tap from a container for any reason or when the container is empty. This will avoid beverage or residue being blown out through the tap-hole or scattering leakage which often gathers on the barrel-head. Usually when a tap is to be removed from a container, air-cock 6 is first closed, but the pressure within the container is still sufficiently above normal atmospheric pressure to cause a violent exhaust which carries fluid or sediment with it, if the pressure is not 100 first reduced slowly to normal atmospheric pressure, and the vent which I provide at the tap permits this without disturbing other connections.

In the arrangement of Figure 4, when it is 110 desired to flush a beverage line before a container is empty, the air pressure to that container is shut off at its valve 31, and then the pressure in the container is reduced by operating air vent 34 to allow air to escape therefrom. The air pressure 115 in the container will now be lower than the normal pressure from tank E and socket 28 is attached to the service faucet for that container and the faucet opened, whereupon the air pressure from tank E will drive the beverage fluid 120 back into the container. Tap cock 29 is then closed and air tube 27 disconnected from the service faucet. Water may now be admitted to the flushing pipes by opening either or both cocks 125 37 and 38, and either one of the cocks 43 or 44 according to which beverage line is to be flushed. If the beverage line 18 connected with container C is to be flushed, cock 43 and service faucet 20 will be opened, thus permitting either hot or cold water, or first hot and then cold, according 130 to the operation of cocks 37 and 38, to flow through piping 41, 25, nozzles 2 and 1, pipe 18 and connected cooling coil, and out through faucet 20. When sufficiently flushed, the water supply is shut off at cocks 43, 37 and 38, and cock 45 is opened. 135 Air pipe 27 is then connected either to faucet 20 or nozzle 46, or successively to both, to drive the water out of the piping. When the piping is cleared of water, cock 45 is closed and tap cock 29 and air valve 31 will be opened, and when the 140 beverage fluid appears at faucet 20 it is closed and that line will be again ready for beverage service. The same procedure will be followed when container C is empty, except in that case the air tap 3 is disconnected and tap cock 29 will 145 be allowed to remain open until the tap is flushed into the container, whereupon that cock is closed and the tap disconnected from the container, and then the flushing flow will be as just described. In this instance, when the flushing operation is 150

completed, taps T and 3 will be attached to a fresh container and then tap-cock 29 and air-cock 31 will be opened, and as the beverage begins to flow at faucet 20, it is closed, and the line will be ready for service. The same operation may be performed when flushing the piping connected with a tap of the type T', except that when a container is empty, the disconnecting and retapping is done with a single device T' instead of the separate beverage and air taps as shown in connection with container C, and when flushing after the container is empty the tap is loosened in the tap hole to allow the air to escape before flushing the tap. After the tap is flushed, cock 29 is closed, the tap removed from the container and the flushing proceeds as before.

From the foregoing description it will be seen that the flushing of the beverage line may be done at any time with practically no loss of time or waste of beverage fluid, and without breaking any of the pipe connections, other than making the usual disconnections of the air and beverage taps at the container when same is empty.

What I claim is:

25. 1. In beverage dispensing apparatus, the combination of a container tap having two nozzles, a beverage pipe connected between one of said nozzles and a dispensing faucet, a flushing pipe connected between the second nozzle and a flushing supply, a pressure supply pipe connected with the container, means for regulating the pressure supplied to the container, a manually controlled air-vent for reducing the pressure in the container independently of said regulating means, an auxiliary pressure pipe adapted for connection to the outlet of the dispensing faucet, and means for regulating the pressure in said auxiliary pressure pipe, whereby the beverage is returned to the container under reduced pressure to clear the beverage pipe preparatory to flushing said pipe from the tap out through the dispensing faucet.
2. In beverage dispensing apparatus, the combination of a container tap having a stop-cock and two nozzles, a beverage pipe connected between one of said nozzles and a dispensing faucet, a pressure supply pipe connected with the container, means for regulating the pressure

supplied to the container, a manually controlled air-vent for reducing the pressure in the container independently of said regulating means, an auxiliary pressure pipe adapted for connection to the outlet of the dispensing faucet, means for regulating the pressure in said auxiliary pressure pipe, whereby the beverage is returned to the container under reduced pressure to clear the beverage pipe preparatory to flushing said pipe, and a flushing pipe connected between the second nozzle on the container tap and a flushing supply, whereby the beverage line may be flushed from the tap out through the dispensing faucet and down through the tap-cock and pipe into the container.

3. In beverage dispensing apparatus, the combination with beverage and pressure piping and container tap, of interconnected flushing piping and control cocks, a vent located at the tap for permitting reduction of the pressure in the beverage container without adjusting the pressure controller in the pressure line, and an auxiliary pressure connection arranged for connection to the dispensing faucet thereby providing back pressure for driving the beverage fluid from the pipe line back into the container, and whereby the beverage piping may be flushed without disconnecting the piping system from the beverage container and without loss of beverage fluid from the pipe line.

4. In beverage dispensing apparatus, the combination of a beverage container tap having a stop-cock and two nozzles, a service faucet, a beverage pipe connected between one of said nozzles and said faucet, a flushing pipe connected between the other of said nozzles and a water supply pipe, a control cock for the water supply, an air or gas pressure supply and means for supplying said pressure to a beverage container, a vent located at the tap for permitting reduction of the pressure in the beverage container without adjusting the pressure controller in the pressure line, and an auxiliary pressure connection for reversing the pressure in the beverage pipe to drive the beverage fluid back into its container.
